(57) CLAIM

The ornamental design for an air bag cover, as shown and described.

DESCRIPTION

FIG. 1 is a front perspective view of an air bag cover showing our new design;

FIG. 2 is a front elevational view thereof;

FIG. 3 is a left side elevational view, the right side being a mirror image thereof;

FIG. 4 is a top plan view thereof; and,

FIG. 5 is a bottom plan view thereof.

In the drawings, the broken lines depict portions of the article that form no part of the claimed design.
